UNITED STATES PATENT OFFICE.

MORRIS BERNHARD, OF NEW YORK, N. Y., ASSIGNOR TO MORRIS BERNHARD CO., OF NEW YORK, N. Y., A CORPORATION OF NEW YORK.

ADJUSTABLE ORNAMENT FOR DRAPERY TIE BACKS.

Application filed November 18, 1924. Serial No. 750,685.

To all whom it may concern:

Be it known that I, MORRIS BERNHARD, a citizen of the United States, and a resident of the city of New York, borough of 5 Manhattan, in the county and State of New York, United States of America, have invented a new and Improved Adjustable Ornament for Drapery Tie Backs, of which the following is a full, clear, and exact description.

This invention has relation to draperies and has particular reference to tie-backs therefor which are provided with ornaments.

Heretofore it has been the general practice to permanently secure the ornament to the tie-back cord, thereby preventing the shifting of the ornament with respect to the cord to various positions in accordance with the 20 desire of the decorator.

It is, therefore, the outstanding object of the present invention to loosely mount the ornament on the tie-back cord so that the same may be adjusted longitudinally there- 25 of to suit the taste.

The invention furthermore comprehends an adjustable ornament for drapery tie-backs which is extremely simple, does not materially add to the cost of production, 30 and which is highly effective in its purpose.

With the above recited and other objects in view, the invention resides in the novel construction set forth in the following specification, particularly pointed out in the 35 appended claims and illustrated in the accompanying drawings, it being understood that the right is reserved to embodiments other than those actually illustrated herein to the full extent indicated by the general meaning of the terms in which the 40 claims are expressed.

In the drawings—

Figure 1 is a view illustrating a drapery equipped with an ornamented tie-back constructed in accordance with the invention 45 and illustrating respectively in full and

dotted lines the ornament in its adjusted positions.

Fig. 2 is a view of the tie-back removed from the drapery.

Fig. 3 is a sectional view taken approximately on the line indicated at 3—3 in Fig. 2.

Referring to the drawings by characters of reference, 10 designates a tie-back cord 55 of the usual construction and 11 an ornament therefor, which ornament is provided with a looped portion or element 12 for slidably associating said ornament with the tie-back cord whereby the same may be longitudinally adjusted thereon and frictionally maintained in its adjusted position. 60

From the foregoing construction it will be seen that the ornament may be arranged either at the inner secured end of the tie-back cord as illustrated in dotted lines in Fig. 1, at the outer bight portion of the tie-back cord as illustrated in dotted lines in Fig. 1, or in an intermediate position as illustrated in full lines in Fig. 1, and this 70 without the necessity of having to unstitch the ornament and restitch the same at the place desired.

I claim:

1. A drapery tie-back comprising a tie-back cord, and an ornament mounted on the cord for longitudinal adjustments.

2. A drapery tie-back, an ornament for said tie-back, and means of connection between the tie-back and ornament for permitting of longitudinal adjustment of the ornament on the tie-back.

3. A drapery tie-back, an ornament for said tie-back, and means of connection between the tie-back and ornament for permitting of longitudinal adjustment of the ornament on the tie-back, said means comprising a loop on the ornament embracing the tie back and frictionally engaging the same to maintain itself in adjusted position on the cord.

MORRIS BERNHARD.
